UNITED STATES PATENT OFFICE.

ARTHUR W. FRISKEY, OF CHICAGO, ILLINOIS.

BINDER.

SPECIFICATION forming part of Letters Patent No. 787,368, dated April 18, 1905.

Application filed February 24, 1902. Serial No. 95,218.

To all whom it may concern:

Be it known that I, ARTHUR W. FRISKEY, a citizen of the United States, residing at Chicago, in the county of Cook and State of Illinois, have invented certain new and useful Improvements in Binders, of which the following is a full, clear, and exact specification.

My invention relates to that class of binders employed for holding loose leaves or sheets and usually comprising a pair of covers having hinged portions in one of which one or more impaling-pins are planted and passed through registering perforations in the leaves and the other cover, combined with means for securing the latter cover firmly to the impaling-pins, and thereby holding it snugly against the leaves; and my invention has for one of its important objects to provide an impaling-pin which shall be composed of detachable sections, so that the length thereof may be varied to suit the thickness of the leaves between the covers.

Another object of my invention is to provide improved and simple means for clamping one of the covers down against the leaves.

With these ends in view my invention consists in certain features of novelty in the construction, combination, and arrangement of parts by which the said objects and certain other objects hereinafter appearing are attained, all as fully described with reference to the accompanying drawings, and more particularly pointed out in the claims.

In the said drawings, Figure 1 is a perspective view of a binder embodying my improvements. Fig. 2 is an enlarged detail sectional view of a part of one of the covers, taken on the line 2 2, Fig. 6. Fig. 3 is a sectional view taken on the line 3, Fig. 4, the covering or binding of the cover being omitted. Fig. 4 is an enlarged detail section taken on the line 4, Fig. 1. Fig. 5 is a transverse section taken on the line 5, Fig. 2. Fig. 6 is a similar section taken on the line 6, Fig. 2. Fig. 7 is a longitudinal sectional view of my improved impaling-pin. Fig. 8 is a similar view thereof, showing the pin extended in length for a thicker book or block of leaves. Fig. 9 is a detail longitudinal sectional view of one of the sections of the im-

paling-pin, and Fig. 10 is a similar view of another one of such sections.

1 2 are the covers proper, which are suitably hinged in the usual manner to strips 3 4, extending along the edge thereof, and through which latter it is customary to pass the impaling-pins. The covers proper, 1 2, may be composed of pasteboard or any other suitable material provided with a covering 5, which may be also carried around the strips 3 and serve to constitute the hinge between the strips 3 and the covers proper. These strips 3 are each composed of a flattened tube 6, whose ends are closed by caps 7 8. The lower threaded ends 9 of the impaling-pins 65 are passed through suitable perforations in the tubes 6 and secured in blocks 10, forced into and held by the lower one of the tubes 6, as shown in Figs. 3 and 4, each of the blocks 10 filling the cross-section of the tube. 70 The upper tube forms a guide and housing for the clamping-blocks, which grip the impaling-pins, and thereby lock the strip 3 firmly against the pile of leaves. These clamping-blocks are shown at 11 12, and they 75 are provided in their outer sides with semi-circular notches 13 14, which are adapted to fit around the impaling-pins and when the blocks are wedged apart to pinch the pins with sufficient force to prevent the upper 80 strip 3 from being raised. This wedging action of the blocks 11 12 is produced by a screw 15, threaded in the block 12 and having its extremity swiveled in the block 11, the latter being provided with a socket extending 85 part way through it, in which the end of the screw-rod 15 is inserted and held by a cross-pin or key 16 passing through the block 11 and engaging in a peripheral groove 17 in the rod. The opposite end of the screw may be 90 held in place by a pair of cross-bars 18, riveted in opposite sides of tube 6 and passing on either side of the screw. The outer extremity of the screw is provided with a key-post 19, arranged opposite a keyhole 20 in the 95 cap 8. By the means described it will be seen that when the screw 15 is turned in one direction the gripping-blocks 11 12 will be forced apart for clamping the impaling-pins and when turned in the opposite direction the im- 100

paling-pins will be released to permit the upper cover-strip 3 to be raised for inserting or removing the leaves, the tube 6 constituting means for holding and guiding the blocks 11 5 12 in these movements.

The impaling-pins (one or more of which may be used, two being shown) are each composed of the detachable sections, as shown in Figs. 7 to 10, inclusive. The lower section, 10 which carries the threaded end 9, is composed of a tube 21, in which is firmly secured an internally-threaded nut 22. In this nut 22 is screwed the lower end of a short rod 23, which passes through and is virtually a part of a sleeve 15 24, around which is secured a collar 25, much shorter than and arranged at about the mid-length of the sleeve 24, as more clearly shown in Fig. 9, so that the ends of the collar 25 will form abutting shoulders for the upper end of 20 the tube 21 and the lower end of a tube 26, which fits over the upper end of tube 24 and in which is secured a nut 27, threaded on the upper end of rod 23. Into the upper end of nut 27 is threaded the lower end of a rod 23^x, 25 belonging to another one of the sections, like that shown in Fig. 9, 24^x being the part corresponding to 24 and 25^x the collar corresponding to the collar 25. This pin is built up in this manner by means of the described 30 sections until the desired height is attained, and the upper end is finished off by means of a cap 28, fitted down over the end of sleeve 24 or 24^x and threaded on the upper end of rod 23 or 23^x, the cap 28 being provided with 35 a knurled head 29, if desired, for preventing the upper strip 3 from being accidentally displaced and also affording means for unscrewing the cap 28.

The numbers 23 24 25 constitute the male

section, whose tenons 24 are received in the 40 socket ends of the female sections comprised by members 26 27, and by these means it will be seen a post or pin of the desired height may be built up, the base-sections 21 22 and cap-section 29 fitting either end of any one of 45 the male sections.

Having thus described my invention, what I claim as new therein, and desire to secure by Letters Patent, is—

1. In a binder the combination with the 50 cover, of an impaling-pin comprising a plurality of male sections, a plurality of female sections, a base-section and a cap-section; each of said male sections comprising a shoulder at its largest diameter with a tenon at each end 55 thereof and a male screw smaller than the tenons projecting from each of the latter, said female sections each consisting of a socket at each end for receiving either of said tenons and a female screw at the inner end of each of 60 said sockets for receiving either of said male screws, said base-section comprising a female screw for receiving either of said male screws and means for attaching it to the cover, and said cap-section comprising a female screw 65 for receiving either of said male screws.

2. In a binder, the combination of a hollow cover member, impaling-pins passing therethrough, two grip-blocks arranged loosely in and guided by said hollow cover member, and 70 a screw swiveled in and immovable longitudinally with relation to one of said blocks and threaded in the other of said blocks for forcing said blocks against said impaling-pins.

ARTHUR W. FRISKEY.
